UNITED STATES PATENT OFFICE.

JOHN W. BURGEWITZ, OF MUSKEGON, MICHIGAN.

ENVELOP.

1,106,623

Specification of Letters Patent. Patented Aug. 11, 1914.

Application filed April 15, 1913. Serial No. 761,381.

To all whom it may concern:

Be it known that I, JOHN W. BURGEWITZ, citizen of the United States, residing at Muskegon, in the county of Muskegon and 5 State of Michigan, have invented certain new and useful Improvements in Envelops, of which the following is a specification.

This invention relates to improvements in envelopes, more particularly to the class of 10 safety envelopes for protecting the contents from surreptitious access, and has for one of its objects to improve the construction and increase the efficiency and utility of devices of this character.

15 Another object of the invention is to provide a simply constructed envelop which effectually protects the contents and without materially increasing the expense of manufacture or interfering with the ordinary uses 20 of the envelop.

With these and other objects in view the invention consists in certain novel features of construction as hereinafter shown and described and then specifically pointed out 25 in the claim.

The improved envelop may be constructed of any required size and of any required material, and may be applied to any of the 30 various forms of envelopes in which a closure flap is employed, and it is not desired therefore to limit the invention to any special form of envelop, but for the purpose of illustration the improvement is shown applied to an ordinary envelop, and in the drawings 35 illustrative of the preferred embodiment of the invention: Figure 1 is a perspective view of a conventional envelop from the mail receiving side and shown in open position. Fig. 2 is a similar view with the envelop 40 closed. Fig. 3 is a transverse section on the line 3—3 of Fig. 2.

45 Corresponding and like parts are referred to in the following description and indicated in all the views of the drawings by the same reference characters.

The improved envelop comprises a body or front portion 10 with back flap 11, and end flaps 12—13 and the closure flap 14. The end flaps 12—13 are foldable upon the 50 body 10 and the back flap 11 is foldable over the folded end flaps with the superimposed portions secured by the usual adhesive. Formed through the overlapping portions of the flaps 11—12—13 are clefts 15 and with 55 branch clefts 16 leading from the main cleft 15 and preferably converging at their inner

ends whereby intermediate tongues 17 are produced which are superimposed when the envelop is closed.

Extending from the closure flap 14 is a 60 tongue 18 and foldable intermediate its ends as shown at 19. Attached to the portion of the tongue in advance of the fold 19 is a reinforcing member 20 which thereby increases the thickness of the tongue externally 65 of the fold. The distance between the "root" 19 or inner portion of the tongue 18 and the fold 25 of the closure flap corresponds to the distance from the fold 25 of the closure flap to the longitudinally extending 70 registering cleft 15, so that when the closure flap 14 is disposed in folded position and the reinforced portion of the tongue 18 thrust through the registering clefts 15 with the reinforced portion of the tongue 18 doubled back upon itself beneath the overlapping portions of the flaps, as illustrated in 75 Figs. 2 and 3 the reinforcing member 20 is thus disposed wholly within the envelop and bearing against the inner face of the 80 inner tongue 17, while the body of the tongue 18 of the closure flap covers and protects the relatively fragile tongues 17. The edges of the closure flap 14 and the inner face of the tongue 18 and likewise the inner face of 85 the reinforcing member are provided with an adhesive indicated at 21, so that when the envelop is to be closed the adhesive will be moistened and thus caused to adhere to the outer surface of the end back flap 11 and 90 the end flaps 12 and likewise adhere to the inner face of the envelop. By this means the envelop is thoroughly secured and any attempt at surreptitious opening will cause the fracture of the relatively light tongues 95 and thus disclose the fact that the envelop has been tampered with.

The improved envelop is also provided with means for quickly opening the same, and consisting in a pull thread 22 located 100 within the envelop with one terminal secured to a stay member 23, preferably of tough paper or fabric, and secured as by cementing against the front 10 of the envelop in one corner, and with the opposite 105 terminal of the thread extending through the opposite end of the envelop and provided with a knot 24 in its outer end. The stay member 23 is located against the folds of the envelop at one corner so that the 110 thread 22 lies against one edge of the envelop on the inside.

The projecting portion including the knot 24 hangs loosely and does not interfere with the handling of the envelop, while at the same time the envelop may be quickly torn 5 open by grasping the knotted end of the thread and pulling upon the latter. The stay member 23 is an important feature of the invention and securely connects the pull thread to the envelop.

10 Having thus described the invention, what is claimed as new is:

An envelop including back and end flaps, said flaps having slits in their overlapping portions and extending longitudinally of 15 the body of the envelop and which register when the envelop is folded, and branch slits

spaced apart and communicating with the longitudinally extending slits and forming tongues which are superimposed when the envelop is closed, a closure flap, a tongue extending from the closure flap and foldable intermediate the ends with the folded portion passing through the longitudinally extending registering slits and concealing and protecting the superimposed tongues. 20 25

In testimony whereof I affix my signature in presence of two witnesses.

JOHN W. BURGEWITZ. [L. s.]
